WAX POWDER APPLICATOR AND
OFFSET ELIMINATOR

William Russell Dreesen, Indianapolis, Ind.
Application October 12, 1950, Serial No. 189,864

2 Claims. (Cl. 118—308)

1. **Apparatus for applying a powder to a web, comprising a hopper having a substantially vertical plate on one side, a side wall on the other side, and a doctor blade on the side wall, a feed roll interposed between the hopper and the doctor blade, and a brush interposed between the feed roll and the doctor blade.**

This invention relates to a powder applicator and ink offset eliminator for use particularly in connection with printing presses.

When a printer prints paper in endless rolls or in separate sheets, it is necessary that he take steps to prevent the offset of ink onto the back of adjacent sheets. In addition to making an impression upon adjacent sheets as aforesaid, the ink has a natural tendency to cause the sheets to stick together. This is commonly called "blocking." Heretofore, various means have been devised to overcome and eliminate offset and blocking problems. Among such means are the heat setting or heat drying method, the slip sheeting method and the steam setting or steam precipitation method. There are, however, disadvantages inherent in each method.

It is, therefore, the primary object of this invention to provide an apparatus which will distribute a wax powder in an even, smooth fashion upon a web, so that the coating or film thus formed will eliminate offset and blocking.

It is a further object of this invention to provide means for recapturing any powder that might otherwise be lost and wasted as it is "sprayed" upon the web.

It is a still further object of this invention to provide a member which serves not only as one side of the feed hopper but also as a doctor blade of adjustable character which will prevent the building up or accumulation of powder upon the feed roll.

The principal feature of the present invention resides in the construction and arrangement of the various parts of the apparatus to accomplish the abovementioned objects.

The full nature of the invention will be understood from the accompanying drawings and the following description and claims:

In the drawings, Fig. 1 is a vertical section view of the invention shown in association with the frame of a printing press and with certain of the printing rolls.

Fig. 2 is an end elevation view of the invention itself.

Fig. 3 is a side elevation view thereof.

In the drawings the frame of the printing press upon which the invention is mounted is shown generally at 10. The press includes the printing rollers 11 of conventional style together with the tension roll 12 and the mill roll 13. The invention is securely mounted upon the press frame by the angle irons 14 and 15. Fixedly secured by the bolts 16 or any other suitable means to said angle irons is the powder feed

hopper 17. This hopper receives the powder within the chamber 18 defined on one side by the substantially vertical plate 19 which is preferably formed of glass or some other suitable substance which has a smooth even surface. The other side of the chamber is defined by the side wall 20 of the hopper and the doctor blade 21. As will be observed by reference particularly to Fig. 1, the plate although substantially vertical is nonetheless slightly inclined towards the hopper side defined by side wall 20 and the doctor blade. Furthermore, the bottom of the plate should either abut the hereinafter mentioned feed roll at a point vertical of its axis or at a point not more than 5 degrees off center from its axis and away from the doctor blade. Proper feeding of wax powder is difficult, and consequently it is very important that the hopper construction be such as to facilitate the desired feeding. The above arrangement accomplishes this result.

Interposed between said plate and blade is the feed roll 22 which is preferably, although not necessarily of Cumberland ground shaft type. The reduced end portions 23 of the shaft have their bearings in the end walls 24 of the hopper. One of said reduced portions extends through an end wall and beyond, it having a gear 25 mounted thereon adjacent its free end. Said gear is provided with a pulley 26 which is connected by the belt 27 to, and is powered by, the electric motor 28 mounted by the bolts 29 to the hopper.

The gear meshes with smaller gear 30 which drives the feed brush 31. This brush is preferably of mane hair type. It is substantially coextensive with the feed roll and is so positioned relative thereto that its bristles engage the roll. By reason of the gear ratio, it is obvious that the brush will rotate at a considerably greater rate of speed than will the roll. Furthermore, the adjacent segments of the roll and brush will naturally be rotating in the same direction. By reason of the higher rate of speed of the brush, it will brush off of the roll the powder

32 which adheres to its surfaces, and will cause the powder to spray downwardly upon the web 33. The direction of travel of the powder spray will, by reason of applicant's construction, be substantially perpendicular to the plane of the web.

In order to shield the brush and to recapture any powder that follows the centrifugal forces set up by the rapid rotation of the brush, there is provided the guard 34. This guard is substantially coextensive with the brush, and

is carried by the lever arms 35 which are pivotally mounted at 36 exteriorly of each end wall. In the event, as aforesaid, that the air currents resulting from the rapid rotation of the brush cause some of the powder particles to move in their path, the guard will prevent their loss, and will guide and direct them once again through the adjacent faces of the brush and roll.

The abovementioned levers also carry the brush as well as the guard, the reduced end portions 37 thereof being journaled therein. In order to permit a change of the relative relation between the faces of the brush and roll, there is provided opposed, threaded bolts 38 above and below each lever adjacent its pivotal connection. These bolts extend through internally threaded lugs 39 secured to each end wall, and as well through lock nuts 40. The free ends of each opposed pair of bolts are adapted to abut the side edges of the lever. When the brush is to be moved slightly away from the roll, it is necessary only to adjust each bolt upwardly. The reverse procedure is followed when the brush is to be brought into closer relation to the roll. The free ends of the bolts are always in engagement with the side edges of each lever, thereby firmly and securely retaining the levers and the brush and guard carried thereby in the desired position.

Regardless of the type of powder used in connection with the invention, and irrespective of the type of roll employed, there will always be some powder adhering to the roll even after it has passed the brush. As a result, in order to prevent a building up or accumulation of powder upon the roll, there is provided the doctor blade 21. This blade is preferably formed of spring metal or the like which is secured at 41 to the longitudinally disposed bar 42. While the natural resiliency of the blade will normally urge it upwardly into engagement with the roll, it is nonetheless desirable to provide the set screws 43 mounted at spaced intervals in the bar. These screws are adjustable upwardly in order to bias the blade into closer relation with the blade.

While there is latitude of choice as to the powder used with the invention, it has been found by experience that a wax powder of petroleum microcrystalline type ground to from 1 to 10 microns in diameter, is preferable. This type of powder has sufficient dryness and hardness to enable it to flow freely through applicant's invention without caking or blocking. Furthermore, it has a softening point low enough to enable it to combine properly with the paraffin compound used in the baths to which the printed paper is subjected after the printing and powdering operations. As a result of the use of the abovementioned powder, the paper presents a smooth, glazed and even surface. Furthermore,

by reason of applicant's invention, any offset or blocking normally occurring after the printing operation is eliminated.

While the invention has been illustrated and described in great detail in the drawings and foregoing description, the same is to be considered as illustrative and not restrictive in character.

The invention claimed is:

1. An apparatus for use with a printing press in applying an offset preventing medium to the freshly printed surface of a sheet or web, comprising a hopper for said medium having an open bottom, a rotating member rotatably connected at opposite ends to the end walls of said hopper and spanning the open bottom of said hopper, means for rotating said member, a rotating brush lying parallel to and substantially coextensive with said member and having means for rotation thereof at a faster rate of speed than said member, said brush normally being operably associated with said rotating member at a point exteriorly of the hopper enclosed surface of said member, and adjustable means for varying the proximity of said brush to said member, said means comprising a pair of substantially L-shaped levers each being pivotally connected at one end to an end wall of said hopper exteriorly thereof, the opposite end of each of said levers having the opposite ends of said brush journaled therein, a pair of opposed lugs connected to each of said end walls exteriorly thereof, said lugs having an internally threaded aperture formed therethrough, and an externally threaded element adjustably disposed in each aperture, a portion of said levers being interposed between the free ends of the elements of each pair.

2. An apparatus as defined in claim 1 wherein in the bottom portions of said hopper are inwardly converged, one of said bottom portions being movable to and fro into and out of engagement with said member, and adjustable means associated with said bottom portion for to and from movement thereof.
